VENEER PATCH CUTTING MACHINE

John Gragg, Olympia, Wash.

Application January 14, 1935, Serial No. 1,613

3 Claims. (Cl. 144—2)

This invention relates to wood patch cutting machines and more particularly to an improved type of machine for cutting patch pieces from veneer strips for use in patching veneer stock where knots, pitch pockets, stains and other flaws have been removed; it being the principal object of the invention to provide a machine for the above stated purpose whereby patch pieces of accurate size may be manufactured rapidly and in an economical manner.

More specifically stated, the objects of the present invention reside in the provision of a machine of the above stated character in which mechanisms are provided for intermittently advancing a strip of veneer from which the patch pieces are to be cut, and adjacent which mechanisms a pair of electrically operated motors are arranged with their driven shafts extending transversely of the direction of advancement of the strip and equipped, respectively, with oppositely facing spherically cupped disk saws so located relative to the strip and to each other that incident to oscillation of the motor in timing with operations of the strip advancing means they will coact to effect the cutting of patch pieces from the strip.

It is also an object of the invention to provide a novel means for effecting intermittent advance movements of the veneer strip and oscillating movements of the saw driving motors.

Other objects of the invention reside in the details of construction of the various parts of the machine, in their combination and in their mode of operation as will hereinafter be described.

In accomplishing these and other objects of the invention, I have provided the improved details of construction, the preferred forms of which are illustrated in the accompanying drawings, whereinafter—

Fig. 1 is a side elevation of a patch cutting machine embodied by the present invention.

Fig. 2 is a top, or plan view of the same.

Fig. 3 is an end elevation of the machine, particularly illustrating the arrangement of the motors and relationship of the saws.

Fig. 4 is a horizontal section, on the line 4—4 in Fig. 3.

Fig. 5 is a side view of one of the motors and its saw; showing the relationship of the saw and veneer strip guideway and the veneer strip clamp plates.

Fig. 6 is a top view of the same parts.

Fig. 7 is a side elevation, showing one of the motor oscillating cams and associated parts.

Fig. 8 is a face view of the cam.

Fig. 9 is a view of the strip advancing ratchet mechanism.

Fig. 10 is a side view of the strip advancing ratchet mechanism, and its actuating crank.

Figs. 11 and 12, respectively, show in plan and edge view, a patch, as cut by the coaction of the saws, from the strip.

Referring more in detail to the drawings—

The operating parts of the present machine are mounted upon a substantial and rigid frame 10 structure of rectangular form, comprising four corner legs 1, joined across their lower ends by channel bars 2 and across their upper ends by angle bars 3. A bed plate 4 is fixed upon these latter bars to form a flat table top. Also, horizontal cross bars 5 are fixed in the frame somewhat below the top and these mount thereon a horizontal bed plate 6 on which the motor oscillating cams and the strip advancing mechanisms are mounted, as will presently be described.

An electric motor 7, for operating the strip advancing means and for oscillating the saw driving motors, is mounted below the plate 6 on supports 8 which are fixed, as seen in Figs. 1 and 3, upon the lower cross bars 2.

The veneer strips from which patch pieces are to be cut, are advanced to the saws within a horizontal guideway 10 extending across the upper bed plate 4. This guideway, as seen in Figs. 2 and 3, is defined by two parallel guide bars 11—11 supported in spaced relation above the bed 4 by a plurality of studs 12, fixed in the plate 4, as seen in Figs. 1 and 5. The veneer patch strips, one of which is designated at 15, are of a width to be advanced within the guideway without lateral play and they are advanced by short, intermittent feed movements by the driving action of paired feed rolls which are located respectively above and below the guideway at spaced intervals therealong, as will now be explained.

By reference particularly to Figs. 1 and 2, it will be observed that there are paired upper and lower feed rolls 16 and 17 at the receiving end of the guideway and these are supported by driving shafts 16' and 17', respectively. At the delivery end of the guideway, there is a similar pair of rolls 18 and 19 mounted respectively by shafts 18' and 19'. Intermediate these two sets of feed rolls, at substantially equally spaced intervals, are feed rolls 20, 21, and 22 located beneath the guideway and mounted respectively by shafts 20', 21', and 22'. Directly overlying these lower rolls are relatively small upper rolls 23, 24, and 25. The driving shafts 16' and 17' for the first mentioned pair of feed rolls are revolvably

mounted in suitable bearing brackets, designated at 26, that are mounted on the top plate 4. The driving shafts 20', 21', and 22' for the other lower rolls are revoluble in bearings 27 fixed on 5 the plate 5, and the supporting shafts for the cooperating upper rolls 23, 24, and 25, revolve in bearings 28 fixed on the guide bars 11-11.

When a veneer strip 15 is inserted between the initial feed rolls 16 and 17, it is advanced by 10 short, intermittent movements, which are effected by a driving connection with the motor 7. This connection comprises a sprocket chain belt 30 that operates about a driving sprocket wheel 31 on the motor shaft 7a and about a sprocket 15 wheel 32 fixed on a horizontal shaft 33, revolubly supported in bearings 34 and 35, mounted in spaced relation, as seen in Fig. 4, on the bed plate 6. On the end of the shaft 33, extended beyond the bearing 35, is a crank arm 36 connected pivotally to a rod 38 which, in turn connects pivotally to the outer end of a crank arm 38 revolubly mounted on a supporting shaft 39 which, at its ends, is supported revolubly in spaced bearings 40-40, as seen best in Figs. 4, 9, and 10. 25 A pawl 41 is pivotally mounted in the crank arm 38 and this pawl is adapted to cooperatively engage a ratchet wheel 42 fixed on the shaft 39.

Fixed on the shaft 39 is a sprocket wheel 44 and a sprocket chain belt 45 operates about the wheel 30 44 and about a smaller sprocket wheel 46 fixed on the driving shaft 20' of feed roll 20. Thus, with each rotation of the crank arm 36, the arm 38 is oscillated. Accordingly, the pawl 41 advances the ratchet wheel 42 a definite interval 35 and this, in turn, rotates the sprocket wheel 44 a like interval which, through the chain belt connection 45 rotates the feed roll 20 for advancement of the veneer strip 15.

Each of the other lower feed rolls is actuated by 40 connection with the shaft 20' of the feed roll 20 so that all will rotate in unison and to the same extent. The driving connections, as illustrated best in Figs. 1 and 2, comprise a sprocket chain belt 48 operating about a driving sprocket wheel 49 on shaft 20' and about sprocket wheels 50 and 51 of a like size on the shafts 16' and 17' of rolls 16 and 17. A sprocket chain belt 52 operates about sprocket wheels 53 and 54 on shafts 20' and 21' to drive the rolls 21. A sprocket chain belt 55 operates about sprockets 56 and 57 on shafts 21' and 22' to drive the roll 22 and likewise a chain belt 58 operates about sprockets 59 and 60 on shafts 22' and 19' to drive the roll 19. The strip 15 is guided between the upper 55 and lower feed rolls and the lower rolls are preferably knurled, as seen in Fig. 3, to aid in advancing the strip and to hold it against possible slippage.

For cutting the patch pieces from the strip 15 there is provided two saw units, comprising electric motors 65 and 66, located at opposite sides of the guideway 10 and one in advance of the other, as seen best in Fig. 2. These motors are disposed with their driven shafts extending transversely of the direction of the guideway. The motors are pivotally supported by means permitting them to oscillate in planes perpendicular to the direction of the strip 15. Each motor is fixed upon a supporting base 68 and these bases are disposed between and pivotally supported by the upstanding arms 69-69 of slides 70 which in turn are movable toward and from the guideway between supporting guide rails 71-71 fixed 70 on the bed plate 4; the means for effecting move-

ment of a slide comprising a bolt 72 fixed in the slide and extended in the direction of movement through a lug 73 fixed on the base plate, with adjusting nuts 74-74' threaded onto the bolt and engaging opposite faces of the lug.

The supporting trunnions 75 about which each motor is adapted to oscillate in its support are in axial alignment and this bisects the axial line of the motor shaft, as will be observed by reference to Fig. 3.

Fixed on the extended ends of the motor shafts 65' and 66' are disk saws 76-77 each of which is spherically cupped about a center which is the point of intersection of the motor shaft and its axis of oscillation.

The saws of the two motors are alike in size and curvature and are oppositely faced and are so arranged that by oscillation of the motors, they may be caused to cut downwardly through the advanced veneer strip 15. The arcuate cuts 20 thus to be made through the strip by the first saw will be intersected by the cuts made by the second saw, thereby to cut out patch pieces of the shape illustrated in Figs. 11 and 12.

The means for oscillating the saw units is illustrated best in Figs. 1, 3, and 4. As observed in Fig. 4, there is a horizontal shaft 80 disposed at a right angle to shaft 33, and supported revolubly in bearings 81 and 82 on the bed plate, 6. This shaft is driven from the latter shaft by intermeshing bevel gears 83 and 84 of like size fixed, respectively, to these shafts. Mounted on the shaft 80, in spaced relation are inside cams 85 and 86 and associated with these cams are lever arms 87 and 88 having ends pivotally fixed, as at 89, to mounting brackets 90 fixed to the base plate 6. These levers extend operatively across the upper face portions of the cams. The lever 87 has a follower 91 engaging within the slot of cam 85 while lever 88 has a follower 92 likewise engaging cam 86. The upper ends of the lever arms are connected, respectively, by rods 93 and 94 with brackets 95 and 96 fixed rigidly to and extending downwardly from the mounting bases of the motors. Thus, incident to rotation of the cams, the levers and links effect a definite oscillatory action of the motors whereby their saws are first caused to be actuated downwardly to cut through the strip 15, and are then lifted in the clear of the strip for its advancement. The cams 85 and 86 are so set on the shaft 80 that the motors are oscillated in unison and this motion is synchronized with the operations of the strip advancing ratchet mechanism, so that the strip advances during those periods that the saws are clear of the strip.

Coiled springs 98 and 98' are attached to the upper ends of the lever arms 87 and 88 and to the outer edges of bed plate 4 to maintain smoothness of motion of the saws.

In order to insure that the patch pieces when cut free of the strip will be separated therefrom, an arm 99 is attached to the supporting base 68 of the motor 66 and is extended to a position overlying the strip at a point beyond the saws. This arm 99 has a downwardly offset end 99' arranged to register with the position of a severed patch in the strip 15 while the strip is at rest so that when the motor base is rocked downwardly it will push the patch from the strip. The removed patches drop into a chute 100 which may lead to any suitable receptacle.

It will be mentioned here that the size of the patch pieces may be changed by inward or outward adjustment of the two motors relative to

the guideway and this is accomplished by an adjustment of the slides 70 through manipulation of the nuts 74 on the bolts 72.

To prevent possible slippage of the veneer strip 15 in the guideway during a sawing operation, and more especially to hold the patch piece against binding the saw while being cut from the strip, the latter is passed adjacent each saw between clamp plates 102 and 103, as seen best in Fig. 5. The under plate 102 in each instance is stationary and is supported by certain of the bolts 12 which mount the guide bars 11. The overlying plate 103 in each instance extends lengthwise of the strip and is supported centrally by a stud 104 extending upwardly through an opening in a plate 105 fixed on the rail 11 at that side with a coiled spring 106 surrounding the studs and resting on the plates and pushing upwardly on heads 104' of the studs and normally releasing the clamping action. Arms 108 are fixed to the motors and extended upwardly to positions at which their ends will contact the upper ends of the studs to push them downwardly when the motors swing down to cutting position, so that the veneer strip and that part comprising the patch piece will then be securely gripped between the clamp plates as the saw operates thereon. When the motors rock back to raised position, the springs lift the plates 103 and the veneer strip is again free for advancement by the feed rolls.

Assuming the device to be so constructed, it is only necessary to feed the veneer strips into the machine between the feed rolls 16 and 17 and the operating mechanisms then advance it by intermittent movements to the saws which are actuated, by the oscillating action of their driving motors, into the strip during its periods of rest thereby to sever the patch pieces from the strip. On lifting of the motors the strip is advanced an interval slightly more than the length of a patch and then the saws again operate.

This machine is accurate, easily operated and economical.

Having thus described my invention, what I claim as new therein and desire to secure by Letters Patent is:—

1. A patch cutting machine comprising a guideway, means for feeding a strip of veneer along the guideway, a motor support at each side of the guideway, a motor base pivoted in each support, an electric motor fixed on each base and having its shaft extended over the strip; the axis about which each motor pivots being perpendicular to

and intersecting the axial line of its shaft and permitting the extended end of the shaft to be swung directly toward and from the strip, a spherically cupped disk saw fixed on each motor shaft; said saws being oppositely faced and each being cupped about the point of intersection of the axial line of the motor shaft which mounts it and the pivoting axis of the motor, means for intermittently actuating the feeding means to advance the strip definite distances, means operating in timing therewith to oscillate the motors to cause their saws to cut into the strip while at rest, thereby incident to advancement of the strip to form arcuate cuts which, by reason of advancement of the strip, will intersect to define and sever patch pieces from the strip, guides for the motor supports, and means for adjusting the supports therein toward and from the guideway and for fixing them at set positions.

2. A machine of the character described, comprising a guideway, means for feeding a strip of veneer along the guideway, a motor base pivoted at each side of the guideway, an electric motor mounted on each base and having its shaft extended over the strip, a spherically cupped disk saw fixed on each motor shaft; said saws being oppositely faced, means for intermittently actuating the feeding means to advance a strip definite distances, means operating in timing therewith to oscillate the motor bases to cause the motor saws to cut into the strip while at rest and thereby to form arcuate cuts, which incident to advancement of the strip, will intersect to define and sever the patch pieces from the strip, and an arm fixed to one of said motor bases and movable therewith to eccentrically engage and displace said patch pieces from the strip openings.

3. A machine of the character described, comprising a guideway, means for intermittently feeding a strip of veneer or the like along the guideway, a motor pivotally supported at each side of the guideway, a cupped saw fixed on each motor shaft, means operating in timing with the intermittent feeding means to oscillate the motors to cause their saws to cut into the strip while at rest, thereby to form arcuate cuts which define the patch pieces, and an arm fixed to one of said motors and movable therewith to eccentrically engage and displace said patch pieces to cause them to drop through the strip openings defined by the saw cuts.

JOHN GRAGG.
